UNITED STATES PATENT OFFICE.

HERBERT H. DREW, OF WATERLOO, WISCONSIN.

FLUE-DRAFT-CONTROLLING DAMPER.

1,209,686.

Specification of Letters Patent. Patented Dec. 26, 1916.

Application filed April 21, 1916. Serial No. 92,592.

To all whom it may concern:

Be it known that I, HERBERT H. DREW, a citizen of the United States, and resident of Waterloo, in the county of Jefferson and 5 State of Wisconsin, have invented certain new and useful Improvements in Flue-Draft-Controlling Dampers; and I do hereby declare that the following is a full, clear, and exact description thereof.

10 The present invention relates to new and useful improvements in damper structures for stoves or furnaces, and is more particularly directed to the provision of an improved damper adapted for association with 15 the draft pipe of a stove or furnace to provide a means of communication with the outer atmosphere whereby air may be drawn into the flue pipe to lessen the draft exerted through the fire and thus reduce the combustion. 20

It is an important object of the present invention to provide such a damper arrangement which may act automatically to admit air into the flue pipe upon a sudden 25 heavy draft in the pipe being created whereby a constant maximum of draft may be maintained through the fire to thus conduce to a desired constant rate of combustion.

30 The rate of combustion desired may at times vary, and it is therefore further an object to provide a damper arrangement having a variable resistance to its operation by the draft.

35 It is still further an object to provide a damper and variable control means therefor which is of exceedingly simple construction whereby it can very readily and economically be associated with the draft flues of 40 stoves or furnaces and whereby a maximum ease of operation and durability in use is procured.

With the above and other objects and advantages in view the invention resides more 45 particularly in the novel combination and formation and arrangement of parts more particularly hereinafter described and more particularly pointed out in the appended claims.

50 In the drawings: Figure 1 is a vertical sectional view through a portion of a furnace or stove flue with which my improved damper structure is associated. Fig. 2 is a detailed sectional view on the line 2—2 55 of Fig. 1 and showing the means for mounting the control rod of the damper.

Referring now more particularly to the accompanying drawings, 5 designates the vertically extending flue pipe of a stove or furnace, and this flue pipe is provided with 60 a lateral extension 6 which telescopically receives the sleeve portion 7 of an annular damper carrying body plate 8, the peripheral edge of the plate being extended beyond the said sleeve 7. Depending from a 65 pivot connection 9 at the upper portion of the inner face of the body plate is a damper plate 10 which normally closes the central opening of the plate 8. Thus an excessive draft through the pipe 5 will draw air inwardly through the extension 6 and the draft through the fire will be correspondingly lessened. At the same time inasmuch as the present damper arrangement is 70 preferably disposed adjacent the stove or furnace in the flue, a portion of the indrawn air will enter the fire chamber and will dispose in a blanket over the fire to further discourage an undesired degree of combustion. 75

To provide a means for adjustably varying the resistance offered by the damper plate 10 to the suction of air into the flue, a control rod 11 is passed through the upper portion of the body plate 8 and a groove 7' struck in the adjacent sleeve portion 7, whereby a guide channel is formed in conjunction with the pipe portion 6 and pivotally depending from the inner end of this rod is a link 12 pivotally connected with 80 an arm 13 extending inwardly from the inner end of an upwardly bowed weight bar 14, the other end of this weight bar being pivotally connected at 15 to the damper plate. Thus by shifting the control rod 85 11, the point of pivotal suspension of the link 12 will be correspondingly shifted whereby the bodily vertical movement of the weight incident to an inward swinging 90 movement of the damper plate may be varied to thus vary the force necessary to swing the damper plate inwardly against the holding action of the said weight. The link 12 preferably comprises a loop between 95 the stretches of which the intermediate portion of weight bar is held and the pivotal securement of this loop to the control rod preferably consisting in bending the inner portion of the rod in the form of an eye 100 which receives the link loop, the free extremity of this inner end being directed downwardly and outwardly at 17 to form 105 110

a stop adapted to engage the damper plate upon movement of the control rod to its outer limit of movement, whereby the damper plate may thus be locked against opening movement. This control means thus provides a readily adjusted means for varying the maximum amount of combustion permitted in the stove or furnace.

I claim:

- 10 1. The combination with a horizontally swinging damper plate of a rod slidable in the direction of swinging movement of the plate, a link pivotally connected with the rod, and a weight member pivoted to 15 the link and to the damper plate.
2. The combination with a horizontally swinging damper plate of a rod slidable in the direction of movement of the plate, a loop member pivotally depending from 20 the rod, an upwardly bowed weight member extending through the loop and having

one end pivoted to the plate and an arm extending inwardly from the other end of the member and pivotally connected with the loop.

- 25 3. The combination with a horizontally disposed pipe member of an apertured body plate, a sleeve extending from the body plate and engageable in the pipe portion, a damper pivoted thereto to close the aperture thereof, said plate and sleeve being provided with a guide channel, a control rod slidably passed through said channel, a link pivotally connected with the rod and a weight pivoted to the link and to the damper plate.

In testimony that I claim the foregoing I have hereunto set my hand at Edgerton, in the county of Rock and State of Wisconsin.

HERBERT H. DREW.
